UNITED STATES PATENT OFFICE

2,647,573

VENETIAN BLIND TAPE RETAINING PIN

Robert W. Meyer, Elyria, Ohio, assignor to The
Guarantee Specialty Manufacturing Co., Cleve-
land, Ohio, a corporation

Application June 4, 1951, Serial No. 229,771

3 Claims. (Cl. 160—178)

1

This invention relates to Venetian blinds, particularly to a novel form of tape retaining pin, adapted to be used therein for fastening the tape to certain of the operating parts of a blind.

The tape retaining pin of this invention, is primarily adapted to be used with Venetian blinds, wherein the tilt bar or unit therein is comprised of metal or the like material, and also in those instances which avail of metal bottom rails for such blinds, the said pin providing ready means for assembling and disassembling tape to such blind, both in the manufacturing operations, as well as in preparation for cleaning the tape and other parts of the blind.

In the copending application of Wright and Zay, Ser. No. 187,622, filed September 29, 1950, there is disclosed a Venetian blind construction of the type above referred to, wherein the head bar of novel type is illustrated. This particular head bar includes certain tape supporting members, to which the tapes upon assembly may be fastened by suitable serrated pins, the said supporting members being provided with suitable loop receiving openings in which the tape ends are inserted.

It has been found that the serrated pins are satisfactory, but the present invention discloses an improved form of pin which is not as readily displaceable from its position, since the same is formed with suitable means to prevent undesirable movement of the pin out of position in the loops whereby the tapes are retained in connection with the supporting members therefor.

In particular, the tape retaining pins of this invention are comprised of metal stampings or the like, having relatively long narrow body portions and formed integrally therewith a head member at each end thereof. Each head member above referred to includes a stop section formed so as to extend slightly from one edge of the body, and adapted to coact with the body portion of the supporting member, so as to prevent movement of the pin once it has been positioned in the loop of the tape. As further insurance against displacement of the pin, the head is provided with a notch formed between a lug or ear extending from the opposite edge of the body of the pin and the body proper, each said notch being adapted to receive and engage the corresponding edge of a tape.

It is therefore an object of this invention to provide a novel form of tape retaining pin,

which may be formed of a metal stamping or the like, and of simple construction whereby the pin may be readily placed in the loop of a Venetian blind tape, or removed therefrom, and yet not be subject to undesired displacement therefrom.

It is a further object of this invention to provide a tape retaining pin in which suitable stop members are formed, adapted to coact with a supporting member to which the tape is to be attached, so as to effect positive retention of the tape in its position.

It is a further object of this invention to provide a tape retaining pin having a novel form of head member at each end thereof, which includes stops and notches, the notches being adapted to coact with corresponding tape edges so as to prevent undesired displacement of the pin.

It is a further object of this invention to provide a tape retaining pin including the stop portions and the notches in the head members, which instrumentalities will coact with the tape supporting member and tape respectively, to effectively maintain the tape in connected relation with the supporting member therefor.

Other and further objects of this invention will be hereinafter set forth in conjunction with description of the same and illustrated in the drawings wherein:

Figure 1 is a plan view of a tape retaining pin formed in accordance with this invention.

Figure 2 is an end elevational view showing the retaining pins in place on a tape supporting member, the Venetian blind tapes connected therewith, and illustrating the manner in which the whole is assembled in a Venetian blind, although certain parts of the Venetian blind are omitted.

Figure 3 is a sectional view taken about on the line 3—3 looking in the direction of the arrows in Figure 2, illustrating in somewhat more detail the manner of engagement of the retaining pin and supporting member, as well as the interengagement of the notches in the retaining pin with the tape.

Figure 4 is a sectional view taken about on the line 4—4 looking in the direction of the arrows in Figure 2.

Referring now to Figure 1 in the drawing, the tape retaining pin of this invention includes the relatively long narrow body 1, preferably formed of thin sheet metal or the like, the said body 1 including substantially identical heads 2 at opposite ends thereof. The heads 2 are comprised

of stops 3, the latter having substantially arcuate shaped form. It will be apparent that the stops 3 are formed at one edge and integral with the body 1 of the pin. At the opposite edge of the body 1, and forming a part of the heads 2 are the lugs or ears 4. These lugs or ears 4 are formed so as to extend toward one another, and intermediate the said lugs or ears 4 are the notches 5, formed between the said lugs and the edge of the body 1, as will be apparent.

Referring now to Figures 2 to 4 inclusive, there is illustrated a tape supporting member generally designated 6. This tape supporting member is more particularly illustrated and described in the said copending application of Wright and Zay, previously mentioned, and includes a body section 7 substantially rectangular in outline, the same being provided with suitable pulley supporting means generally designated 8, extending upwardly therefrom. At the ends of the body 7 are the depending ears 9, adapted to receive therein the main supporting member of the Venetian blind, which in this illustration is preferably a substantially U-shaped member of generally rectangular form, not completely illustrated but being more particularly disclosed in the said Wright and Zay application.

At the opposite edges of the body 7 are the depending portions 10, which portions 10 extend throughout the length of the body 7 preferably and are further provided with loop receiving openings 11, clearly shown in Figure 4. The loop receiving openings 11 are adapted to receive the loop ends 12 of the Venetian blind tape generally designated 13, the said loop ends being formed by means of folding back respective ends of the tape on themselves and suitably stapling them as at 14, the same being illustrated in Figure 3. The tape 13 is of course provided with the usual ladder members 15 upon which the slats of the blind are supported.

With the parts of the Venetian blind as illustrated in Figure 2, it will be noted that the tape ends 12 forming the looped portions thereof, have been inserted in the loop receiving openings 11, and thereafter the tape retaining pins illustrated in Figure 1 have been inserted. It will be apparent that with the pins positioned as illustrated in Figure 2, and as clearly shown in Figures 3 and 4, stops 3 have assumed positions at opposite edges of the supporting member 7. It will also be noted that the notches 5 at the opposite ends of the pin are so spaced as to engage the respective edges of the tape loop.

In view of the foregoing it will be apparent that any tendency on the part of the pin to work toward either edge of the tape will be obviated by reason of provision of the notches in the respective heads 2, as well as the stops 3 adapted to coact with the body section 7 of the supporting member. It should be noted at this point that it is within the contemplation of this invention, to avail of either the stops 3 with the body 1 of the pin without resorting to the notches

5, so as to retain the pin in place, or conversely to resort to the notches 5 thus depending upon the stops 3 to prevent such displacement of the pin as is not desired.

It should also be noted that the particular disclosure herein described, wherein the tape retaining pins are availed of for connecting the tape at the ends thereof with a tape supporting member or the like, may by the same token be availed of to connect the said tape at the bottom ends thereof with the bottom rail, wherein said bottom rail is provided with suitable loop receiving opening in the same manner as is shown in connection with the tape supporting members in the head of the Venetian blind.

In view of the foregoing, it will be apparent that there is shown and described a novel form of tape retaining pin, which enables the ready connection of tape ends in assembly of a blind and also which retaining pins may be removed when desired, but do not of themselves readily work out of position so as to permit the tape to become accidentally disconnected.

Having thus shown and described my invention, what I claim as new and desire to secure by Letters Patent of the United States is set forth in the following claims:

1. In a Venetian blind, in combination, a tape supporting member, having a tape connection portion formed with an opening, a tape having a looped end passing through said opening, a retaining pin seated in said loop, head members at opposite ends of the pin, each head member having a stop for engaging an adjacent edge of the tape connecting portion of the supporting member, and said head members each having a notch to receive an adjacent edge of the tape at said loop.

2. The combination as claimed in claim 1 wherein the stops are at one edge of said pin, and the notches are formed at the opposite edge.

3. A retaining pin of the class described comprising a relatively long, narrow, flat body, a head member at each end of said body, each head member comprising a stop formed at one edge of said body, an ear formed at the opposite edge of said body, and a notch formed in each ear, said notches extending in opposite directions and said ears extending toward each other, the said stops being spaced a greater distance apart than the said notches.

ROBERT W. MEYER.
